(57) **CLAIM**

The ornamental design for an applicator for a surgical stapler buttress, as shown and described.

DESCRIPTION

FIG. 1 is a perspective view of an applicator for a surgical stapler buttress, showing our new design;

FIG. 2 is a front elevational view of the applicator for a surgical stapler buttress of FIG. 1, the opposite rear elevational view being a mirror image thereof;

FIG. 3 is a right side elevational view of the applicator for a surgical stapler buttress of FIG. 1;

FIG. 4 is a left side elevational view of the applicator for a surgical stapler buttress of FIG. 1; and,

FIG. 5 is a top plan view of the applicator for a surgical stapler buttress of FIG. 1, the opposite bottom plan view being a mirror image thereof.

1 Claim, 4 Drawing Sheets
